UNITED STATES PATENT OFFICE

172,706

TABLE

Hugh J. Davey, Frankfort, Ind., and
Robert O. Bextel, Detroit, Mich.

Application September 8, 1953, Serial No. 26,718

Term of patent 7 years

(Cl. D33—14)

To all whom it may concern:

Be it known that we, Hugh J. Davey and Robert O. Bextel, citizens of the United States, residing at Frankfort, Indiana, and Detroit, Michigan, respectively, have invented a new, original, and ornamental Design for a Table, of which the following is a specification, reference being had to the accompanying drawing, forming a part hereof.

Fig. 1 is a perspective view of a table, showing our new design; and

Fig. 2 is a side elevation thereof.

We claim:

The ornamental design for a table, as shown.
